(57) **CLAIM**

The ornamental design for a display screen with graphical user interface, as shown and described.

DESCRIPTION

The sole FIGURE is a front view of a display screen with graphical user interface showing the new design.

The outermost broken lines showing an electronic device illustrate environmental subject matter and form no part of the claimed design. The remaining broken lines show portions of the graphical user interface, and form no part of the claimed design. The outermost solid line showing the edge of the display screen forms part of the claim. The gray shading depicts a contrast in appearance and forms part of the claimed design.
